UNITED STATES PATENT OFFICE.

RAYMOND VAN IDERSTINE, OF GLEN RIDGE, NEW JERSEY.

DISPLAY CARTON.

Application filed March 27, 1923. Serial No. 628,082.

To all whom it may concern:

Be it known that I, RAYMOND VAN IDERSTINE, a citizen of the United States, and a resident of Glen Ridge, in the county of Essex and State of New Jersey, have invented a new and Improved Display Carton, of which the following is a full, clear, and exact description.

This invention has relation to display cartons and aims as its principal object to produce a display carton which is so constructed as to render the same practically proof against theft of the contents when in display position.

As a further object the invention contemplates a display carton which is constructed from a single piece of material and so folded and arranged that the surfaces which are printed and displayed are on one face thereof whereby stock which is coated only on one side may be employed in the manufacture of the same.

As a further object the invention provides a display carton which is fully closed when not in display position whereby the same constitutes a highly efficient package for the contents without the necessity of employing a string, a wrapper or other fastening means to hold the same in closed condition.

The invention furthermore aims to produce a display carton which is extremely simple in its construction, inexpensive to manufacture, which is flat and compact when folded whereby the same may be nested for shipment, and which may be readily set up for filling.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a perspective view of the carton set up for display.

Fig. 2 is a longitudinal sectional view therethrough.

Fig. 3 is a similar view illustrating the carton in closed condition.

Fig. 4 is a plan view of the blank from

which the carton is constructed prior to the gluing of the same.

Fig. 5 is a similar view after the gluing and illustrating the carton in collapsed position for storage and shipment.

Fig. 6 is a sectional view taken approximately on the line 6—6 of Fig. 2.

Fig. 7 is a sectional view similar to Fig. 6 when the carton is set up and prior to the folding of the end flaps.

Referring to the drawings by characters of reference, the box consists of a body having a top wall 10, side walls 11 and a bottom wall 12, which walls are preferably constructed integral, one of the side walls 11 being provided with a flap 13 which is glued or pasted to the inner face of the free edge of the bottom 12. The front of the box is formed by interlocking flaps 14 which are preferably integral extensions from the front edges of the side walls 11 and which are turned inwardly and interengaged with each other when the box is set up. The cover flap 15 formed preferably as an integral extension of the front edge of the bottom wall 12 is provided which is turned upwardly to overlie the interlocking flaps 14 and is provided with a bendable end 16 which is inserted between the upper edges of the interlocking flaps and the front edge of the top wall. The rear wall consists of an inner flap 17 which is formed preferably as an integral extension of the bottom wall 12 and is provided with a bendable end 18 which is frictionally engaged between the upper edges of the inturned flanges 19 formed preferably as integral extensions from the rear edges of the side walls 11. The inner flap 17 at its juncture with the bottom wall 12 is formed with a medial slit 20 which is coincident with its line of folding and the purpose of which slit will be hereinafter set forth. The inner flap 17 is further provided with a substantially horseshoe shaped cut 21 which provides a door 22 and a doorway 23 to be used as a means for gaining access to the interior of the box from the rear of the same when in display or set up condition. The rear wall further includes an outer flap 24 which is formed preferably as an integral extension of the top wall 10 and is provided at its free lower edge with a projecting tongue 25 approximately the same length as the slit 20 where by said flap is held in covering relation over

the inner flap 17 when the carton is filled and packed for shipment with its contents. The flap 24 is provided further with a semi-circular cut 26 whereby the outer end portion 27 may be bent to lie substantially parallel thereto with the major portion of the flap 24 projecting upwardly and rearwardly at an angle to constitute a display flap upon which printed matter may be inscribed. The 10 same is held in this position by the portion 24 which serves as a support by the insertion of the tongue 25 between the rear edge of the top 10 and the bendable end 18 of the inner flap 17.

15 It will thus be seen that from the foregoing construction a display carton is provided which when set on a counter serves the purpose of advertising the contents while at the same time acting to minimize 20 the probability of theft of the contents due to the fact that access to the contents is gained only through the doorway or vending opening 23 in the inner flap which constitutes the rear wall. It will be further 25 noted that all of the exposed or displayed surfaces which are to be printed are on one side of the stock from which the carton is constructed whereby the carton may be constructed from a stock which is noted only 30 on one face.

I claim:

1. An advertising and display carton, comprising a box-like body having completely closed front, top, side and bottom 35 walls, adapted to present surfaces for receiving and displaying advertising indicia relative to the contents, the rear wall having a dispensing opening for removing and vending the goods contained thereby, a closure flap normally closing said opening 40 whereby the goods is housed and protected against handling or theft, and a combined display flap and supplemental covering for the rear wall adapted to respectively project upwardly and rearwardly when in display 45 position and to cover the rear wall for retaining the closure flap in closed position.

2. A carton for counter advertising and display, comprising a box-like body having 50 completely closed front, top, side and bottom walls adapted to present outer surfaces for receiving and displaying advertising indicia relative to the contents thereof, a rear wall having a dispensing opening for removing 55 and vending the goods therefrom, a closure flap normally closing said opening, and a combined display and supplemental covering flap for the rear wall hinged to swing

in the same direction as the dispensing opening covering flap and scored transversely 60 to be bent upon itself when in display position, and a locking tab carried by the free edge of the display flap for insertion between the upper wall of the body and the upper end of the rear wall, and a keeper slit 65 at the juncture of the rear wall and the bottom wall for receiving the locking tab when the display flap is in covering relation to the rear wall.

3. A display carton comprising a box-like 70 body having a vending opening in its rear wall, a closure flap therefor, a display flap adapted to be bent transversely upon itself to extend upwardly and rearwardly from the upper rear corner of the box body when 75 in display position, a locking tab at the free end of the display flap insertable between the upper wall of the box and the upper end of the rear wall for holding the display flap in its display position, and a slotted portion 80 at the juncture of the rear wall and the bottom constituting a keeper for receiving the locking tab of the display flap whereby to maintain the display flap in covering relation to the rear wall for retaining the closure flap for the vending opening in close 85 relation thereto.

4. In a counter display and advertising carton, constructed from a single sheet of material, which includes integral closed bottom, side and top walls, and a closed front wall, a rear wall hingedly connected to the bottom wall and provided at its upper free end with a bendable retaining terminal insertable beneath the rear end of the top wall, 90 a substantially semi-circular slotted portion in the rear wall providing a rear vending opening for the carton and an integral closure flap, and a slotted portion at the juncture of said rear wall and the bottom wall, 95 in combination with a combined display and supplemental closure flap hingedly secured to the rear edge of the top wall and transversely bendable, said flap having a locking pad at its free end respectively engageable 100 between the terminal of the rear wall and the rear end of the upper wall to retain the flap in double display position projecting upwardly from the rear of the carton, 105 said locking tab being further engageable in the slotted portion at the juncture of the rear wall and the bottom wall to retain the combined display and covering flap in covering relation to the rear wall for holding the vending opening flap in closed position.

RAYMOND VAN IDERSTINE.
